UNITED STATES PATENT OFFICE

EDWARD F. HOGAN, OF CHICAGO, ILLINOIS, ASSIGNOR TO Q. R. S. DE VRY CORPORATION, OF CHICAGO, ILLINOIS, A CORPORATION OF ILLINOIS

INSULATOR AND CLAMP FOR USE IN ELECTRICAL WORK

Application filed October 20, 1928. Serial No. 313,916.

My invention relates to clamping devices and has for its object more particularly the provision of a device of this character which is adapted to grasp an insulated conductor and to removably hold it in place in an insulator into the interior of which said insulated conductor projects.

More particularly my improved device is adapted for use in connection with the mounting of a high potential insulated conductor within an insulator that is adapted to carry a high potential device such as a gaseous conduction tube which may, for instance, be of the order of the well known neon advertising sign.

My invention in its preferred form contemplates the provision of a device having several indenting elements which are adapted to be indented in the insulating covering of the conductor. The device has additional means by virtue of which in its preferred form, it may be removably secured to the insulator, preferably by spring or snap action. The device then also has certain aligning features by virtue of which the parts are held in their proper relationship.

I will describe my invention more in detail by referring to the accompanying drawings in which—

Fig. 1 shows a side view of my improved device mounted in place upon an insulator and holding the conductor in place; and

Fig. 2 is a similar view at right angles thereto.

In Fig. 1 I show an insulator 10 as adapted to support a gaseous conduction tube 11 and which is adapted to receive its current from an incoming conductor 12. The tube itself has an electrode 13 and the inner connections between the conductor 12 and the electrode 13 are shown and claimed in my pending application, Serial No. 331,898, filed January 11, 1929.

The incoming conductor 12 has a coating of insulation 14. The mouth 15 of the insulator into which the insulated conductor extends is preferably circular in form.

My improved device in the form herein shown consists of a body portion 16 which encircles about 180° of the mouth 15 of the

insulator. At its free extremity it has downwardly projecting arms 17, each provided at their extremities with prongs 18. These prongs are adapted when the device is mounted in place to be indented in the insulating coating of the insulated conductor and their indenting is brought about by sliding a ring 19 over these arms into the final position shown in Figs. 1 and 2. The arrangement is such that the prongs may move outwardly a trifle after the ring has moved over the protuberant along the prong into the position shown, but this retractile action is not sufficient to release the insulated conductor.

The body portion 16 also has an aligning element 20 which projects inwardly and engages the lower face of the mouth 15. The body portion 16 also has upwardly extending fingers 21 which have inwardly bent portions 22 adapted to project into slots 23 provided in the outer side walls of the mouth 15. These fingers 21 are resilient and permit of the ready and quick attachment and detachment of my improved device. The structure, however, is sturdily built so that the connection when made is substantial.

It will be seen that many modifications may be made from this exact structure without departing from the spirit of my invention.

Having, however, thus described one form which my invention may take, what I claim as new and desire to secure by Letters Patent is:

1. A clamp of the character described adapted to secure an insulated conductor so as to project into a hollow insulator comprising a pair of prong-like elements adapted to be indented in the insulated covering of said conductor, means for uniting said elements, means whereby said elements and uniting means may be attached to said hollow insulator, and a slideable clamp for indenting said prong-like elements in said insulated covering.

2. A clamp of the character described adapted to secure an insulated conductor so as to project into a hollow insulator comprising a pair of prong-like elements adapted to be indented in the insulated covering of said conductor, means for uniting said elements,

means whereby said elements and uniting means may be attached to said hollow insulator, and a slidable ring for indenting said prong-like elements in said insulated covering.

5 3. In combination, a hollow insulator, an insulated conductor projecting into said insulator and a clamp for clamping the conductor in place comprising a body portion having spaced projecting resilient prongs for hooking into the insulated covering of the conductor, and having spring fingers for attachment of the body portion to the insulator, said insulator having means receiving said fingers to hold them in place.

10 4. In combination, a hollow insulator, an insulated conductor projecting into said insulator, and a clamp for clamping the conductor in place comprising a body portion having spaced projecting resilient prongs for hooking into the insulated covering of the conductor, and having spring fingers for attachment of the body portion to the insulator, said insulator having recesses formed therein receiving said fingers to hold them in place.

15 5. A clamp for connecting a conductor having a covering of insulating material to a hollow insulator into which said conductor extends comprising a body portion substantially semi-circular in form having at its extremities oppositely directed resilient projections, the projections extending in one direction having hooks for embedding in the covering of the conductor and the projections extending in the opposite direction being offset to form holding portions to receive the insulator.

20 6. A clamp for connecting a conductor having a covering of insulating material to a hollow insulator into which said conductor extends comprising a body portion substantially semi-circular in form having at its extremities oppositely directed resilient projections, the projections extending in one direction having hooks for embedding in the covering of the conductor and the projections extending in the opposite direction being offset to form holding portions to receive the insulator, said body portion having a shoulder intermediate its ends forming a stop for aligning the body portion at the end of the insulator.

25 In witness whereof, I hereunto subscribe my name this 18th day of October A. D., 1928.

EDWARD F. HOGAN.
